SPACER DEVICE FOR MULTIPLE GLAZED UNITS

Oscar D. Englehart, Brackenridge, Pa., assignor to Pittsburgh Plate Glass Company, Allegheny County, Pa., a corporation of Pennsylvania

Application March 28, 1952, Serial No. 279,141

5 Claims. (Cl. 299—24)

1

This invention relates to window constructions and more particularly to an improved spacer device for multiple glazed units.

Multiple glazed units comprise two or more panels of glass spaced one from the other to provide an insulating air film between adjacent panels. It is known to utilize hollow metal spacer devices containing a desiccant composition therein and having openings or diffusion plugs permitting the desiccant to absorb moisture from the air films entrapped between the glass panels.

One object of this invention is to provide an improved spacer construction in the form of a rolled lock seam tube which is relatively inexpensive to make and fabricate into a desiccant containing spacer for multiple glazed units.

Another object of this invention is the provision of a novel desiccant-containing spacer device not requiring drilled openings or diffusion plugs to permit the access of air to the desiccant.

A still further object of this invention is the provision of a novel desiccant containing tubular spacer device having a knurled edge lock seam construction permeable to air.

A still further object of this invention is the provision of a novel spacer construction of rolled metal tubing of rectangular cross section easily handled and fabricated into a spacer unit for multiple glazed window constructions.

Other objects and advantages of the invention will become more apparent from the following detailed description of a preferred embodiment thereof.

In the drawing, Figure 1 is a perspective view of a short section of a spacer device embodying the principles of my invention.

Figure 2 is a sectional view, somewhat enlarged, of the spacer shown in Figure 1.

Figure 3 is a sectional view, somewhat enlarged, of a modified form of spacer device.

Figure 4 is a sectional view of a portion of a multiple glazed window unit utilizing the spacer device shown in Figures 1 and 2.

Referring to the drawings, the spacer device is in the form of a metal tube 10 having a lock seam 11 extending along the length thereof. The tube 10 is preferably of rectangular cross section, but may be of any cross section, and the central enclosed space may be filled with a desiccant 12, as shown in Figure 4. The lock seam 11 may be formed by conventional metal rolling apparatus, and comprises one edge portion 14 of the metal forming the tube 10 having the other edge portion 15 wrapped around it. Before the seam forming operation, the edge or marginal portion 55 may be used in multiple glazed units having only

2

15 is knurled to provide a plurality of lateral grooves 16 therein. The grooves 16 are provided on both faces of the marginal edge portion 15, and the edge of portion 15 is also knurled to provide a notched edge 17.

The spacer device may be formed by shaping flat aluminum strips into the cross section illustrated. The spacer tubing may be formed from any suitable metals such as aluminum, stainless, or carbon steels, and the like, of .010 inch to .020 inch thickness. Such tubing is relatively inexpensive when compared to the cost of suitable extruded aluminum tubing. The channels or grooves 16 and 17 resulting from the knurling operation provide a multiplicity of passageways from the outside of the spacer 10 to the inside thereof for permitting circulation of air from outside the spacer into contact with a moisture absorbing desiccant within the spacer.

In the modification shown in Figure 3, the lock seam 21 is provided inside the spacer tube 20, rather than outside as illustrated in Figures 1 and 2. The spacer 20 is preferably of rectangular cross section. The marginal portion 24 is enclosed by the other marginal portion 25, and portion 25 is knurled on both faces to provide lateral grooves 26 and a notched edge 27. As in the Figure 2 construction, the grooves 26 and notched edge 27 of the Figure 3 modification provide a multiplicity of channels permitting air to have access to the inside of the spacer tube 20.

The spacer tubes described are utilized in multiple glazed units to space the glass panels from one another to form an air film between each pair of glass panels. As shown in Figure 4, the spacer 10 is positioned between the marginal portions of glass panels 31 and 32, and a channel frame member 33 is provided to hold the panels and spacer together as a multiple glazed unit. The spacer 10 contains a desiccant 12, such as activated alumina, anhydrous calcium sulfate, or the like. A sealing compound 34, such as a dispersion of carbon black in polyisobutylene, is provided in the space between the edges of panels 31 and 32, the bottom of spacer 10 and the channel frame member 33 to provide a unit having an effective vapor seal. The passageways formed by the knurled edge portions of the lock seam 11, as shown in the enlarged Figure 2 illustration, provide for access of air in the film between panels 32 and 33 to the desiccant 12 within the spacer 10, for the removal of moisture from said air film. It is to be understood that the spacer device shown and described herein may be used in multiple glazed units having only

two glass panels 31 and 33, or may be used in units having more than two glass panels, and in such cases a spacer device 10 is used between the marginal portions of each adjacent pair of glass panels.

The spacer unit shown and described is easily handled and fabricated by cutting to desired lengths and securing together by welding, brazing, or the like. The provision of the lock seam type of joint provides a strong tubing, and the provision of the knurled edges to form air passageways through the seam eliminates the necessity for drilling air holes or the installation of diffusion plugs. The knurled edge seam also provides a relatively rigid tubular device because the knurled edges prevent slippage along the rolled seam. The seam 11 is rolled sufficiently tight to prevent the desiccant 12 within the tube from entering the air space between glass panels 31 and 32, but loose enough to permit moisture to diffuse from the air space into the desiccant 12 within the spacer tube 10.

It will be apparent to those skilled in the art that various modifications and variations in the nature and arrangement of the elements of the spacer construction are possible without departing from the spirit of this invention or the scope of the appended claims.

What I claim is:

1. A spacer construction for a multiple glazed unit, said spacer comprising a tubular member having a longitudinal seam extending along the length of one side thereof, said seam including a pair of overlapped surfaces, one of said overlapped surfaces having a series of transversely extending spaced grooves therein, said grooved surface being in contact with the other of said surfaces, whereby said grooved surface defines a multiplicity of passages through said seam, and a desiccant located within said tubular member.

2. A spacer construction for a multiple glazed unit, said spacer comprising a tubular metal member of substantially rectangular cross section formed from a strip of sheet material, the marginal portions of said material being overlapped and interlocked into a longitudinal seam along one side of said tubular member, the surfaces of one of said marginal portions having a plurality of spaced grooves therein, said grooves

providing a multiplicity of passages through said seam, and a desiccant located within said tubular member.

3. A spacer construction for a multiple glazed unit, said spacer comprising a tubular sheet metal member of substantially rectangular cross section, said member having a longitudinal interlocked seam along one side thereof, one of the metal surfaces of said seam being knurled with a plurality of spaced grooves extending transversely of the length of said seam, said grooves defining with other surfaces of said seam a multiplicity of passages extending through said seam, and a desiccant located within said tubular member.

4. A spacer construction for a multiple glazed unit, said spacer comprising a tubular metal member of substantially rectangular cross section, said member having a longitudinal seam of overlapped interlocked marginal portions positioned outward of the plane of the seam side of said member, one of said interlocked marginal portions being knurled with a plurality of spaced grooves, said grooves defining with other portions of said seam a multiplicity of passages through said seam and a desiccant located within said tubular member.

5. A spacer construction for a multiple glazed unit, said spacer comprising a tubular metal member of rectangular shape, said member having a longitudinal seam of overlapped interlocked marginal portions extending along one side of said member, said overlapped marginal portions being within said tubular member, one of said marginal portions being knurled with a plurality of spaced grooves defining passages through said seam, and a desiccant located within said tubular member.
